(57) **CLAIM**

The ornamental design for an ice cream machine substantially as shown and described.

DESCRIPTION

FIG. 1 is a perspective view of the first embodiment of an ice cream machine with a sliding lid in a closed position;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a perspective view of the first embodiment of an ice cream machine with the sliding lid in an open position;

FIG. 8 is a front view thereof;

FIG. 9 is a back view thereof;

FIG. 10 is a right side view thereof;

FIG. 11 is a left side view thereof;

FIG. 12 is a top view thereof;

FIG. 13 is a perspective view of the second embodiment of an ice cream machine with the sliding lid in a closed position;

FIG. 14 is a front view thereof;

FIG. 15 is a back view thereof;

FIG. 16 is a right side view

FIG. 17 is a left side view thereof;

FIG. 18 is a top view thereof;

FIG. 19 is a perspective view of the second embodiment of an ice cream machine with a sliding lid in an open position;

FIG. 20 is a front view thereof;

FIG. 21 is a back view thereof;

FIG. 22 is a right side thereof;

FIG. 23 is a left side view thereof; and,

FIG. 24 is a top view thereof.

(Continued)

The broken lines depict unclaimed portions of the ice cream machine only and form no part of the claimed design.
